US0D1090199S

(12) **United States Design Patent** (10) **Patent No.:** **US D1,090,199 S**
(45) **Date of Patent:** **** Aug. 26, 2025**

(54) **FORK**

(71) Applicant: **Sabert Corporation**, Sayreville, NJ (US)

(72) Inventor: **Yohanan Siskindovich**, Florham Park, NJ (US)

(73) Assignee: **Sabert Corporation**, Sayreville, NJ (US)

(**) Term: **15 Years**

(21) Appl. No.: **29/904,473**

(22) Filed: **Oct. 6, 2023**

(51) **LOC (15) Cl.** **07-03**

(52) **U.S. Cl.**

USPC **D7/653**

(58) **Field of Classification Search**
